souri

Application September 23, 1947, Serial No. 775,720

12 Claims. (Cl. 112—2)

1

This invention relates to methods of and apparatus for inserting draw cords in bags, more particularly to methods and apparatus of this class for converting prefabricated bags to draw cord bags.

Among the several objects of the invention may be noted the provision of a method of and apparatus for inserting a draw cord through the fabric of a bag adjacent its mouth to provide a draw cord closure for the bag; the provision of a method and apparatus of the class described for the conversion of prefabricated bags to draw cord bags wherein the draw cord may be held to pull it tight at any point along its length; and the provision of apparatus for the purpose described which is reliable, easy and safe to operate, and capable of a high rate of production. Other objects will be in part apparent and in part pointed out hereinafter.

The invention accordingly comprises the elements and combinations of elements, steps and sequence of steps, features of construction and manipulation, and arrangements of parts which will be exemplified in the structures and methods hereinafter described, and the scope of the application of which will be indicated in the following claims.

In the accompanying drawings, in which one of various possible embodiments of the invention is illustrated,

Fig. 1 is a perspective view of a bag having portions of its fabric adjacent its mouth gathered to form pleats, in accordance with an initial phase of the method of this invention;

Figs. 2 and 3 are end views of the mouth end of the bag illustrating successive steps in the method of inserting a draw cord in the bag;

Fig. 4 is a perspective view of the finished draw cord bag;

Fig. 5 is a front elevation of an apparatus embodying the invention;

Fig. 6 is a plan view of the apparatus;

Fig. 7 is an enlarged section taken on line 7—7 of Fig. 6, showing parts in their operative positions, and omitting a guard;

Fig. 8 is an enlarged vertical section taken substantially on line 8—8 of Fig. 6, showing the guard;

Fig. 9 is an end elevation of Fig. 8 viewed from its left, parts being broken away and shown in section;

Fig. 10 is a vertical section taken substantially on line 10—10 of Fig. 8, omitting the guard;

Fig. 11 is an enlarged plan view of a needle unit;

2

Fig. 12 is an enlarged vertical section taken on line 12—12 of Fig. 5;

Fig. 13 is a vertical section taken on line 13—13 of Fig. 12;

Fig. 14 is a vertical section taken on line 14—14 of Fig. 13;

Fig. 15 is a view on a reduced scale of Fig. 13 as viewed from its right;

Figs. 16 and 17 are enlarged horizontal and vertical sections, respectively, of the eye end of the lower needle of the needle unit; and,

Fig. 18 is a piping and wiring diagram.

Similar reference characters indicate corresponding parts throughout the several views of the drawings.

Referring now to the drawings, Figs. 1—4 illustrate the essential method of this invention for inserting a draw cord in a bag. Fig. 1 illustrates a prefabricated bag 1, such as an open-mesh fabric fruit or vegetable bag, having the usual in-turned side seams 3, and a bottom fold 5. The first step in the method of this invention comprises gathering the portions of the bag fabric in opposite side walls of the bag adjacent its mouth to form two sets of pleats, as illustrated at 7 and 9 in Figs. 1—4.

A needle 11, herein illustrated as a hollow needle having an eye 13 at its pointed end, is threaded with cord 15, drawn from a supply (not shown), and thrust completely through the set of pleats 7, to thread the cord therethrough. It will be understood that the free end of the cord initially extends from within the hollow needle out through its eye 13. A second needle 17 having an eye 19, herein illustrated as an open-ended slot adjacent the pointed end of the needle, is thrust completely through the other set of pleats 9. Needle 17 is initially unthreaded. The free end of the cord 15 is then drawn out of needle 11, and threaded into the eye 19 of needle 17 (Fig. 2). This is accomplished simply by hooking the cord into the open-ended slot forming the eye.

Both needles are then pulled back out of the two sets of pleats, as illustrated in Fig. 3. Needle 17 pulls a length of cord from the supply through the hollow needle 11, and draws it through the upper and lower sets of pleats 7 and 9 to provide a length of cord loosely interwoven with the bag fabric adjacent the mouth of the bag.

The cord 15 is then cut at a point adjacent the pointed end of needle 11, so as to leave this needle threaded. The end of the cord caught in the eye 19 of needle 17 is then pulled out of the eye and secured as by a staple 21 (Fig. 4) to the trailing

end of the cord. Thus, there is provided a draw cord D loosely interwoven with the bag fabric adjacent to its mouth which is wholly free running with respect to the bag fabric, so that the cord may be held at any point along its length and pulled tight to close the bag. It will be understood that the cord is cut to be of such length that, after its ends have been stapled, the pleats may be drawn out so that the mouth of the bag will be flat. It will also be understood that the cord may be pre-cut to the proper length, in which event cutting of the cord upon withdrawal of the needles is not required.

Figs. 5-18 illustrate an embodiment of an apparatus of this invention for converting prefabricated bags to draw cord bags in accordance with the above-described method at a high rate of production. The apparatus includes a pleating device, generally designated 31, for gathering the bag fabric adjacent the mouth of the bag to form the two sets of pleats 7 and 9. This pleating device is mounted upon a supporting frame or table 33 to be at a height convenient for the operator of the apparatus. Also mounted upon the table 33 are a needle unit 35, including an upper needle 37 and a lower needle 39, and a cord cutting and stapling device, generally designated 41.

The pleating device 31 comprises a pair of spaced opposed guides 43 which extend vertically upward from the top of the table 33. Each guide is provided at its lower end with a flange 45 by means of which it is bolted to the table top as indicated at 47. Each guide is formed with a pair of guideways 49 and 51 for guiding a pair of plates 53 and 55 for vertical sliding movement (Fig. 10). Plate 53 slides in guideways 49 and plate 55 slides in guideways 51.

A plate 57 is fixed as by screws 59 to the front faces of the guides 43 to extend vertically upward from the table top and to span the space between the guides. Plate 57 is a mounting for upper and lower sets of fixed pleating pins 61 and 63, respectively. The upper pins 61 are arranged in a horizontal row, horizontally spaced from one another. The lower pins 63 are also arranged in a horizontal row and are vertically aligned with the upper pins. As herein illustrated, there are three upper and three lower pins, but it will be understood that a different number of pins may be provided depending upon the number of pleats desired.

Each of the upper and lower pins is fixed at its rearward end in the fixed vertical plate 57 and extends forward therefrom toward the front of the table. The plate 57 is formed with a pair of vertical slots 65 extending from a point adjacent its upper edge to a point adjacent its lower edge between the upper and lower pins.

The movable plate 53 is a mounting for a lower set of movable pleating pins 67. There are two such pins 67, arranged in a horizontal row, fixed at their rearward ends in the plate 53 and extending forward therefrom through the slots 65. The movable plate 55, which is located in the rear of plate 53, is a mounting for an upper set of movable pleating pins 69. There are two such pins 69, arranged in a horizontal row. These pins are fixed at their rearward ends in plate 55, and extend forward therefrom through the slots 65 in the fixed plate 57.

The above-described arrangement is such that, with the lower movable pleating pins 67 retracted to their lower limit below lower fixed pins 63 and with the upper movable pleating pins 69 retracted to their upper limit above upper fixed pins 61, a

bag I may be placed upon the fixed pleating pins 61 and 63 as illustrated in Fig. 10. The bag fabric at the mouth of the bag surrounds the fixed pins, with its upper wall disposed between the upper fixed pins 61 and the upper movable pins 69, and with its lower wall disposed between the lower fixed pins 63 and the lower movable pins 67. By moving the upper movable pins downward to a point below the upper fixed pins, and by moving the lower movable pins upward to a point above the lower fixed pins, the upper and lower margins of the bag at its mouth may be pleated in the desired manner. The front movable plate 53 is slotted, as indicated at 71. The upper movable pins 69 extend through slot 71 when in their lowered pleating position.

It is preferable to provide a wedge-shaped guide member 73 for facilitating the placement of the bag upon the fixed pleating pins. This guide member is carried by brackets 75 extending outward from the fixed plate 57. It is also preferable to provide a closure plate 76 secured to the rear faces of the guides 43.

Means for moving the movable plates 53 and 55 to advance and retract the lower and upper movable pleating pins is shown to include a double-acting air cylinder 77. This cylinder is pivoted at its upper end, as indicated at 79, to a bracket 81 which depends from the top of table 33. The piston rod 82 of the cylinder extends from its lower end and is pivotally connected at 83 to one end of a rocking lever 85. The latter is pivoted at 87 for rocking movement at the lower end of the bracket 81.

A link 89 is pivotally connected at its lower end to the rocking lever 85 and at its upper end to the movable plate 55, as indicated at 91 and 93, respectively. The pivotal connection 91 is intermediate the lever pivot 87 and the pivotal connection 83 of the piston rod and lever. A link 95 is pivotally connected at its lower end to the other end of the rocking lever and at its upper end to the movable plate 53, as indicated at 97 and 99, respectively.

The arrangement is such that when air under pressure is admitted to the upper end of the cylinder 77 and exhausted from its lower end, piston rod 82 is advanced (moved downward) to rock lever 85 clockwise as viewed in Fig. 5. This pulls link 89 and plate 55 down and drives link 95 and plate 53 up, thereby pulling the upper set of movable pleating pins 69 carried by plate 55 down to their lower limit and raising the lower set of movable pleating pins 67 carried by plate 53 upward to their upper limit (Fig. 7). When air is admitted to the lower end of cylinder 77 and exhausted from its upper end, these motions are reversed and the upper and lower movable pins are retracted to their upper and lower limits, respectively. Means for controlling the supply and exhaust of air from opposite ends of the cylinder will be described subsequently.

The travel of the movable plates 53 and 55 upon an advancing stroke is such as to carry the upper movable pins a substantial distance below the upper fixed pins and to carry the lower movable pins a substantial distance above the lower fixed pins. This is not only to pleat the bag fabric in the manner described, but also to provide sufficient spacing between the upper fixed and movable pins and between the lower fixed and movable pins to receive the upper and lower needles 37 and 39 as they are driven through the upper and lower sets of pleats.

The needle unit 35 is mounted on the top of

table 33 to the right of the pleating device 31 as viewed in Figs. 5-7. The needles 37 and 39 of the needle unit are mounted at their rearward ends in a slide block 101. This block has sliding bearing upon a pair of horizontal guide rods 103, opposite ends of which are fixed in brackets 105 and 107 mounted on the table top. The slide block and needles carried thereby are mounted for reciprocatory movement transverse to the pleating pins. The upper needle 37 is carried in such position that, upon movement of the slide block to the left as viewed in Fig. 5, it will be thrust through the upper set of pleats of the bag fabric between the upper fixed and movable pleating pins. The lower needle 39 is carried in such position that it will be simultaneously thrust through the lower set of pleats of the bag fabric between the lower fixed and movable pleating pins.

The slide block, and the needles carried thereby, are advanced (moved to the left) and retracted (moved to the right) by means of a double-acting air cylinder 109. The cylinder is mounted upon the right end of the table top. Its piston rod 111 extends through an aperture in the right-hand bracket 107 and is fixed to the slide block.

The upper needle 37 is hollow throughout its length except for its pointed end 113. It has an elongate eye 115 adjacent its pointed end. The rear end of the needle is fixed in an aperture 117 which extends completely through the slide block 101 as by means of a set screw 119. The arrangement is such that a cord C may be threaded through the needle from a supply spool (not shown) with its end extending outward through the eye 115.

The lower needle 39 comprises a rod 121 having a point 123 at its forward end (Figs. 16 and 17). Rearward of the point the rod 121 is flattened, as indicated at 125, and this flattened portion is formed with an open-ended slot or eye 127 directed toward the point. The rear end of the rod 121 is fixed in the slide block 101. A tube or sleeve 129 is slidable on the rod 121. This sleeve is somewhat shorter than the rod so as to be capable of some lost motion with respect to the rod. Its forward end is slotted, as indicated at 131, to receive the flattened portion 125 of the rod when the sleeve is moved to the left relative to the rod. The rear end of the rod 121 is fixed to the vertical leg 133 of an L-shaped slider 135. The horizontal leg 137 of this slider is guided for horizontal sliding movement in the guideway 139 of a guide block 141 fixed to the bottom of the slide block 101. A guide pin 143 extends through an aperture in the upper end of the vertical leg 133 of the slider. A compression spring 144, coiled around this pin and reacting from the slide block 101, biases the slider to the left.

The rearward end of the horizontal leg 137 of the slider has a slot 145 for the reception of the upper end of a trip lever 147. The latter is pivoted at 149 in the guide block 141 with its lower end extending below the guide block for engagement by an adjustably fixed stop 151 (Fig. 5). The stop comprises a screw adjustably threaded in a bracket 153 fixed on the table top just forward of the bracket 107.

The above-described arrangement is such that when air under pressure is admitted to the left end and exhausted from the right end of cylinder 109, the slide block 101 and the needles are retracted to their right-hand limiting position as

viewed in Fig. 5. In this position, the lower end of trip lever 147 has engaged the stop 151 and rocked clockwise so that its upper end has pushed the slider 135 and the tube 129 to the right relative to the rod 121 so that the left end of the tube clears the needle eye 127. When air under pressure is admitted to the right end and exhausted from the left end of cylinder 109, the slide block and needles are advanced to the left to their left-hand limiting position, shown in Fig. 7. The needles extend slidably through upper and lower apertures 155 and 157 in the left-hand bracket 105 and through guides 159 and 161 aligned with these apertures.

During the initial phase of movement of the slide block to the left, trip lever 147 moves away from stop 151 and hence the slider 135 and tube 129 are biased to the left relative to rod 121 by spring 144 so that the left end of the tube closes the needle eye 127. During the final phase of movement of the slide block to the left, the guide pin 143 enters an aperture 163 in bracket 105, the slider strikes the bracket, and is biased thereby back to the right. This moves the tube 129 to the right to open up the needle eye 127 so that it may be threaded. Means for controlling the supply and exhaust of air from opposite ends of cylinder 109 will be described subsequently.

The cord cutting and stapling device 41 (Figs. 12-15) comprises the head unit 171 of a conventional wire stapling machine of the type which receives wire from a spool 172, cuts it into staple lengths, and forms and drives the staples. This stapling head unit is mounted above the table top intermediate the pleating device 31 and the needle unit 35 on a vertical mounting plate 173. Plate 173 is fixed to one side of a horizontal mounting plate 175 which is fixed to the table top and extends rearward therefrom. The plane 40 of plate 173 is transverse to the length of the table and it is located to the rear of the table top, extending above and below the latter.

The construction and operation of the stapling head unit are well-known and will not be detailed, but it is to be noted that the unit includes a housing 177 wherein a plunger 179 is vertically reciprocable. The plunger is guided by means of guides 181 which slide in guideways 183 formed in the housing. The plunger is coupled by links 184 and 186 to a staple-driving member 185 to drive the latter downward to drive a staple upon downward movement of the plunger from its retracted position of Fig. 13, and to retract the staple-driving member upon upward return movement to the Fig. 13 position.

The plunger 179 has a pin 187 thereon, connected by a link 189 to an eccentric crank pin 191 on a crank wheel 193. The latter is keyed on a shaft 195 journalled in the vertical plate 60 173. This shaft extends through the plate and is also journalled at its right end, as viewed in Fig. 13, in a journal plate 197 fixed to and spaced from the right of the upper part of the plate 173. A gear 199 is keyed on shaft 195 between plates 65 173 and 197. This gear is in mesh with a gear 201 keyed on a shaft 203 journalled in plates 173 and 197.

The shaft 203 extends out of plate 197. A link 205 is keyed at one end to the extending end of the shaft. The link is pivotally connected at its other end, as indicated at 207, to the piston rod 209 of a double-acting air cylinder 211. The latter is pivoted at its lower end, as indicated at 213, in a bracket 215 fastened to the lower end of 75 vertical mounting plate 173.

The piston rod 209 of the air cylinder 211 is normally in its retracted position of Figs. 13 and 15. When air is admitted to the lower end of the cylinder and exhausted from its upper end, the piston rod moves upward. This rocks link 205 and rotates gear 204 counterclockwise as viewed in Fig. 15, and rotates gear 198 and crank wheel 191 clockwise as viewed in Fig. 15 and counterclockwise as viewed in Fig. 12. Crank wheel 191, acting through the link 186, thereupon drives the plunger 179 and the staple-driving member 185 downward. When air is admitted to the upper end of the cylinder and exhausted from its lower end, the kinematic motions of these elements are reversed and they are returned to their normal retracted positions.

The staple-driving member 185 is positioned for vertical reciprocation transverse to the path of the needles 37 and 39, and intercepting that path. As the member 185 moves downward, a staple-clinching anvil block 217, having an anvil 218 at its upper end, moves upward to meet it. This block is mounted for vertical sliding movement in a tubular guide, generally designated 219. This guide comprises front and rear plates 221 and 223, and a pair of side plates 225 fastened by screws 227 to the side edges of the front and rear plates. The front and rear plates have flanges 229 and 231 fastened to the horizontal mounting plate 175 by screws 233.

The guide 219 extends downward through apertures in the horizontal plate 175 and the table top. It extends upward to a height somewhat above the path of the lower needle 39, consequently its side plates 225 are notched at their upper ends, as indicated at 235, to provide clearance for this needle.

The anvil block 217 has a projection 237 at the left side of its upper end, as viewed in Fig. 13. This projection has a cord-guiding groove 239 in its upper end. The right side of the anvil block is notched out, as indicated at 241 in Fig. 13. This provides an overhanging portion 243 which is vertically bored for slidably guiding a pair of rods 245. These rods are fixed at their upper ends to a cord-clamping bar 247, which extends transversely, spanning the front and rear plates 221 and 223 of the tubular guide 219. The rods and the clamping bar are biased downward by springs 249 located in the notch 241.

The anvil block 217 is moved upward to meet the staple-driving member 185 as the latter moves downward to clinch a staple, and is retracted downward as the member 185 is retracted upward by a cam-operated mechanism actuated by the air cylinder 211. As illustrated in Fig. 12, this mechanism includes a cam 251 keyed on a cam shaft 253 journalled in the plates 173 and 197. A gear 255 is fixed on shaft 253 between these plates, in mesh with the gear 204. The cam actuates a cam follower link 257, which has two cam followers 258 and 261 engaging the cam periphery at points spaced 180°, so that it is moved positively by the cam in both directions. The follower link is retained in position and guided for oscillation by a pin 263 projecting from cam shaft 253 through an elongate slot 265 in the link.

The follower link 257 is pivotally connected at its lower end, as indicated at 267, to one end of a double rocking lever 269. The latter is pivoted at 271 in the lower end of a bracket 273 depending from the horizontal plate 175. The other end of the rocking lever is pivoted at 275 to the lower end of a link 277, the upper end of the lat-

ter being pivotally connected at 279 to the lower end of the anvil block 217.

The parts normally have the position illustrated in Figs. 12-15. When the piston rod 209 of air cylinder 211 moves upward, gear 255 and cam 251 rotate counterclockwise as viewed in Fig. 12. The cam is developed and phased to drive link 257 downward upon such rotation. This rocks the lever 269 counterclockwise as viewed in Fig. 12 and, through link 277, drives the anvil block upward to meet the downcoming staple-driving member 185. When the piston rod is retracted, the parts return to their initial positions.

It will be noted that as the anvil block 217 moves upward, it approaches the clamp bar 247, which is initially biased downward into engagement with the lower ends of notches 280 in the upper end of the tubular guide 219 by the springs 249. As the upper end of the anvil block emerges from the upper end of the tubular guide, it engages the clamp bar, which thereupon moves upward with the anvil block. The purpose of the clamp bar is to clamp the reach of cord extending from the lower needle to the bag on the pleating device in position for stapling. The reach of cord extending from the upper needle to the bag is cut by a knife 281 substantially simultaneously with the stapling operation.

The knife 281 comprises a flat, beveled-edge blade which is guided for vertical sliding movement in a guide block 282 fixed to the lower end of the stapling head unit. The blade slides in a groove 283 in the left face of the guide block, as viewed in Fig. 13, and is retained in the groove by a cover plate 284. This plate has an aperture 285 through which the upper needle 37 of the needle unit travels in the course of its reciprocation. The lower end of the guide block 282 is notched out, as indicated at 286, for passage of this needle. The knife blade 281 normally has a position wherein its lower cutting edge is above the aperture 285. When moved downward from this position it cuts the cord extending through this aperture from the eye of the upper needle to the bag by shearing action against the lower edge of the aperture.

The knife blade 281 is fixed at the lower end of a stem 287. The latter has a head 288 at its upper end. A compression spring 289 coiled around the stem, reacting at its lower end against the guide block 282 and at its upper end against the head, normally biases the knife upward to its normal position in engagement with a pair of stops 290 (Fig. 14). A loop 291 extends upward from the head 288 around the pin 187 of plunger 179. When the plunger 179 moves downward to drive a staple, a shoulder 293 of the plunger (Fig. 13) engages the head 288 and drives the knife downward against the bias of spring 289 to cut the cord. When the plunger moves upward, the knife is driven upward to its retracted position against stops 290 either by spring 289, or by engagement of the pin 187 with the upper end of loop 291 if the knife is jammed by lint or dirt.

The pleating device 31 is preferably provided with a safety guard, generally designated 299. As illustrated in Figs. 8 and 9, the guard comprises a plate 301, preferably of transparent plastic sheet material, which is notched as indicated at 303 to accommodate the pins of the pleating device. A hood 305 surrounds the upper end of the notch, extending forward over the upper movable pleating pins 69. The plate 301 is pivoted for swinging movement by means of part

allel links 307 and 309. The latter are pivoted at their lower ends in the sides of the guides 43. The arrangement is such that the guard is held upward in retracted position by the upper movable pleating fingers when these fingers are in their raised, retracted position, and the pleating device is ready to receive a bag. Otherwise, the guard is lowered. A switch-operating rod 311 projects downward from the lower edge of the guard plate 301 in line with a recess 313 in the 5 portable top. When the guard is in its lowered position, this rod engages and closes a switch 315 mounted in the recess below the table top.

Means for controlling operation of the pleating device 31, needle unit 35 and cutting and stapling device 41 in proper sequence are shown in Fig. 13. Compressed air at proper pressure is supplied from a suitable source (not shown) to the apparatus through a main supply or manifold pipe 321. A pipe 323 connects the manifold 321 to 10 the inlet of a pedal-operated four-way valve 325. This valve is of a conventional type adapted in the raised position of its pedal 327 to connect the valve inlet to one of its ports 329 and to connect its other port 331 to exhaust, and in the depressed position of its pedal to connect the inlet to port 331 and to connect port 329 to exhaust.

The port 329 of the pedal-operated valve 325 is connected by a line 333 including a solenoid valve 335 and a speed control valve 337 to the 15 lower end of air cylinder 17. The port 329 of valve 325 is also connected by a line 339 including a speed control valve 341 to the left end of air cylinder 109. The port 331 of the pedal-operated valve is connected by a line 343 including a solenoid valve 345 and a speed control valve 347 to the 20 upper end of air cylinder 17. The port 331 is also connected by a line 349 including a solenoid valve 351 and a speed control valve 353 to the 25 right end of air cylinder 109.

A pipe 355 connects the manifold 321 to the main inlet of a time-controlled, three-way pilot valve 357. This valve is of a conventional type having an outlet port 359 normally connected to exhaust, but connected to the main inlet for flow of air under pressure through the valve upon actuation thereof. The valve is actuated by an impulse of air through a control inlet 361. Air entering the valve through the control inlet is bled off through an adjustable bleeder outlet 363. The valve remains open for communication from its main inlet to its outlet 359 for a length of time determined by the period required for air to bleed off through 363, then automatically closes off the main inlet and vents the outlet 359 to exhaust.

The outlet 359 of the pilot valve 357 is connected by a pipe 365 to the control inlet 367 of a pressure-actuated four way valve 369. This valve is of a conventional type adapted normally to connect its main inlet 371 to an outlet port 373 and to vent another outlet port 375 to exhaust. When actuated by pressure through pipe 365 and its control inlet 367, it connects the main inlet 371 to outlet port 373 and vents port 375 to exhaust. The main inlet 371 receives air through a pipe 376 connected to manifold 321.

The outlet port 373 is connected by a line 377 including a speed control valve 379 to the upper end of air cylinder 211. The outlet port 375 is connected by a line 381 including a speed control valve 383 to the lower end of air cylinder 211. The arrangement is such that when there is no pressure in pipe 365, valve 369 is set to supply air under pressure through line 377 to the upper end of cylinder 211 and to vent the lower end of

the cylinder to exhaust through line 381. This retracts the piston rod 209 of cylinder 211. When pressure is supplied to control inlet 367 of the four-way valve 369 through pipe 365, valve 369 is set to supply air under pressure through line 381 to the lower end of cylinder 211 and to vent the upper end of the cylinder to exhaust through line 377.

The pilot valve 357 is controlled by a normally closed, tripper-operated control valve 385. Manifold pipe 321 is connected to the inlet of this control valve. Its outlet is connected by a line 387 to the control inlet 361 of the pilot valve 357. Control valve 385 has a pivoted operating lever 389 positioned for engagement by a pivoted tripper 391. The valve 385 is mounted on a supporting plate 393 fixed to the table top (Figs. 6 and 11). The tripper is pivoted on a bracket 395 fixed to the slide block 101 of the needle unit. The tripper is biased counterclockwise, as viewed in Figs. 6 and 11, by a suitable spring 396 (Fig. 11) to an outwardly extending tripping position against a fixed stop 397 extending upward from bracket 395. The tripper may trip freely in clockwise direction. The valve 385 is located for operation by the tripper as the slide block 101, in moving to the right, nears its retracted position. When the slide block moves to the left from its retracted position, the tripper engages the valve-operating lever 389, but does not move it to actuate the valve 385, since the tripper thereupon freely trips clockwise against the bias of its spring.

The solenoid valve 351 is connected in series across a suitable electrical power supply P with three switches, one of which is the previously mentioned guard-controlled switch 315, the other two of which are designated 401 and 403. Switch 401 is mounted upon the bracket 31 for actuation by the rocking lever 85 at the completion of an advancing stroke of the piston rod 82 of air cylinder 17 (Fig. 5). Thus, switch 401 is closed only when the upper and lower movable pleating pins 69 and 67 have been advanced to pleating position, and is otherwise open. Switch 403 is 35 mounted upon the upper end of air cylinder 211 for actuation by a finger 405 extending from piston rod 209 when the latter is in its lowered, retracted position (Figs. 13 and 15). As previously described, switch 315 is closed only when guard 299 is lowered. The circuit including solenoid valve 351 and the switches 315, 401 and 403 is 40 designated 407. All three switches must be closed before this circuit is completed and solenoid valve 351 is energized and opened.

The solenoid valves 335 and 345 are under the control of a switch 409 positioned for actuation by the slide block 101 of the needle unit in its retracted position. As illustrated in Figs. 5, 6 and 11, switch 409 may be mounted upon one of the 45 guide rods 103 in position for engagement by the slide block in its right-hand limiting position. One terminal of the solenoid of valve 335 and one terminal of the solenoid of valve 345 are connected by a wire 411. The other terminals of the 50 solenoids are connected by wires 413 and 415, respectively, to one side of the power supply P. The switch 409 is connected in a line 417 which connects wire 411 and the other side of the power supply. It will be seen that when switch 409 is 55 closed both valves 335 and 345 are energized and opened.

Operation is as follows:

Initially, the piston rods 82, 111 and 209 of air cylinders 17, 109 and 211, respectively, are all 60 retracted, the pedal 327 of pedal-operated valve 75

11

325 being raised. The movable pleating pins 67 and 69 of pleating device 31, the slide block 101 and needles 37 and 39 of needle unit 35, and the plunger 179 and anvil block 217 of the cord cutting and stapling device 41 are all in their retracted positions, as illustrated in Figs. 8-15. Switches 401 and 315 are open, switches 403 and 409 are closed. A cord C is threaded through the upper hollow needle 37 from a supply spool (not shown), the end of the cord extending out through the eye 115 of this needle.

The operator first places a bag 1 upon the fixed pleating pins 61 and 63, opening up the mouth of the bag and thrusting it over the wedge-shaped guide 73 and the fixed pleating pins to a position wherein that portion of the bag fabric adjacent the mouth of the bag loosely surrounds the pins 61 and 63, as illustrated in Fig. 10. The operator then depresses the pedal 327 of the pedal-operated valve 325. This places the inlet of the valve in communication with its port 331 and connects its port 329 to exhaust. Compressed air is therefore supplied to lines 343 and 349. Since switch 409 is now closed, both solenoid valves 335 and 345 are energized and open. Compressed air is therefore supplied through line 343 to the upper end of air cylinder 77. The lower end of the cylinder is vented through line 333 and valve port 329. Since both switches 401 and 315 are now open, solenoid valve 351 is deenergized and closed. Passage of air through line 349 to the right end of air cylinder 109 is therefore blocked.

The piston rod 82 is now driven downward. This rocks the rocking lever 85 to the dotted-line position of Figs. 5 and 18, thereby pulling down the plate 55 and pleating pins 69 thereon and driving up the movable plate 53 and pleating pins 67 thereon to their pleating positions, illustrated in Fig. 7. As the movable pins 67 and 69 move to their pleating positions, they engage the bag fabric between the fixed pleating pins 63 and 61 and loop it into the two sets of pleats 7 and 9.

As the piston rod 82 reaches its lower limiting position, rocking lever 85 closes switch 401. The guard 299 also pivots downward under its own weight, since it rests on the upper movable pleating pins 69. This closes switch 315. Since switch 403 is now closed, the circuit 407 for solenoid valve 351 is completed, and this valve 351 is opened. This admits compressed air through line 349 to the right end of cylinder 109. The left end of cylinder 109 is vented through line 339 and valve port 329 to exhaust (the operator continuing to hold the pedal 327 down). Piston rod 111, slide block 101 and needles 37 and 39 are thereby driven to the left to the limiting position illustrated in Fig. 7. The upper needle 37, threaded with the cord C, is driven through the upper set of pleats 7. The lower needle which is not threaded at this time, is driven through the lower set of pleats 9.

If the operator should inadvertently fail to withdraw her hand from the pleating device before depressing the pedal 327, her hand will necessarily hold the guard 299 raised. Switch 315 will therefore be open, solenoid valve 351 will be deenergized and closed, and the needles will not advance until the operator withdraws her hand to permit the guard to lower. This protects the operator from injury by the needles, which travel rapidly.

As the slide block 101 travels to the left away from its retracted position, the tripper 391 engages but does not operate the valve lever 389, tripping clockwise as previously described. As

12

the slide block approaches its left-hand limiting position, the slider 135 strikes bracket 105 and is moved to the right relative to the lower needle 39. This moves tube 129 to the right relative to needle 39, opening up its eye 127 so that it may be threaded.

The operator, still holding the pedal 327 depressed, now grasps the end of the cord C extending from the eye 115 of upper needle 37 and threads it through the eye 127 of the lower needle. This is quickly accomplished by hooking the cord into the eye.

The operator then releases the pedal 327. Since switch 409 is now open, slide block 101 having previously traveled away from the switch, both solenoid valves 335 and 345 are deenergized and closed, and releasing the pedal has no effect upon cylinder 77 at this time. Solenoid valve 351, however, is energized and open, since all three switches 401, 315 and 403 are closed. With pedal 327 raised, valve 325 is set to place its inlet in communication with its port 329 and its port 331 to exhaust. Compressed air is therefore supplied to lines 339 and 333. Air in line 333 is blocked, however, by solenoid valve 335, which is closed. Air is supplied through line 339 to the left end of cylinder 109 and vented from the right end of the cylinder through line 349 (valve 351 being open) and port 331 of valve 325. This retracts the piston 111, the slide block 101 and the needles 37 and 39 to their retracted, right-hand limiting position wherein the needles are withdrawn from the pleats.

As the slide block 101 moves to the right away from bracket 105, the slider 135 and tube 129 are biased by spring 144 to the left relative to the lower needle so that the end of the cord C is clamped in eye 127 by the left end of the tube (note Figs. 16 and 17). Consequently, as the needles are withdrawn from the pleats, the lower needle pulls the cord through the pleats loosely to interweave it with the bag fabric adjacent the mouth of the bag.

The upper needle 37 is retracted through the aperture 285 so that the upper reach of the cord C extends from the bag through the aperture to the eye of the upper needle (Fig. 13). The lower needle 39 is retracted through the slots 235 in the upper end of guide 219 and between the upper end of the anvil block 217 and the cord-clamping bar 247, so that the lower reach of the cord C extends from the bag between the anvil block and the bar 247 to the eye of the lower needle 39.

As the slide block 101 approaches its right hand limiting position, the trip lever 147 strikes the stop 151. This rotates the trip lever clockwise so that its upper end pushes the slider 135 to the right. This moves the sleeve 129 to the right relative to the rod 121, so that the left end of the sleeve 129 is moved out of clamping position with respect to the cord. This permits ready withdrawal of the end of the cord from the eye 127 of the lower needle 39.

During the return movement of the slide block 101 to the right, the tripper 391 engages and actuates the valve lever 389 momentarily to open the valve 385. This delivers an impulse of air through line 387 and the control inlet 361 to pilot valve 357. This sets the pilot valve to deliver air from pipe 355 through the pilot valve outlet 359 and pipe 365 to the control inlet 367 of pressure-actuated valve 369. The pressure of this air sets valve 369 to supply air through line 381 to the

13

lower end of air cylinder 211 and to vent the upper end of the cylinder through line 377 to exhaust.

Piston rod 209 thereupon moves upward. This causes the staple-driving member 185 to move downward and the anvil block 217 to move upward, as previously described. The upper and lower reaches of cord C are brought together over the staple-clinching anvil 218 and are secured together by the staple 21 which is driven by member 185 and clinched in the clinching groove of the anvil. The reaches of cord are guided into proper position for stapling by the cord-guiding groove 239. Simultaneously, the knife 231 is driven downward, in the manner previously described, to shear the upper reach of cord at the lower edge of aperture 285. This leaves an end of the cord extending out of the eye 115 of the upper needle 37, so that this needle remains threaded for the next cycle of operation.

As the anvil block 217 moves upward to meet the staple-driving member 185, the lower reach of cord C is clamped by the clamping bar 247 against the upper end of the anvil block. This holds the cord in fixed position for staple-clinching purposes.

As soon as air has bled out through the bleeder outlet 363 of pilot valve 357, the latter automatically resets to exhaust the air in line 365. This reverses flow directions in lines 377 and 381 and retracts the piston rod 209 of cylinder 211. The valve 385 is so located and the timing of pilot valve 363 is so adjusted that the piston rod 209 makes a full stroke (advance and return) to operate the cutting and stapling device and to restore the parts thereof to their initial retracted positions all within the time interval that it takes tripper 391 to move from its position of engagement with lever 389 to its right hand limiting position.

When the slide block 101 has been fully retracted to its right hand limiting position, it recloses switch 409. This completes the circuit for solenoid valves 335 and 345. Since the pedal 321 of pedal-operated valve 325 is now raised, air is supplied from the valve port 329 through line 333 to the lower end of cylinder 71. Air is exhausted from the upper end of the cylinder 71 through line 343 and the port 331 of valve 325. This retracts the piston rod 82 and, consequently, retracts the lower and upper movable pleating pins 67 and 69 to their position of Figs. 8-10.

All the parts are now restored to their initial retracted positions. The operator then pulls the completed draw cord bag out of the pleating device, and is then ready to apply another bag to the pleating device and to operate the apparatus through another cycle, in the manner above described.

Thus, the apparatus of this invention is adapted for the rapid conversion of prefabricated bags to draw cord bags. The only manual operations required are the placing of a bag in the pleating device, the operation of the pedal 321, the threading of the cord in the eye of the lower needle 39, the release of the pedal, and the removal of the completed bag. It will be understood that automatic operation of the cord cutting and stapling device may be omitted and that cutting and stapling may be performed manually, if high speed production is not essential. It is contemplated that the ends of the draw cord may be fastened together other than by stapling. Other ways of fastening together the ends of the draw cord, either manually or automatically, will be apparent.

14

In view of the above, it will be seen that the several objects of the invention are achieved and other advantageous results attained.

As many changes could be made in the above constructions and methods without departing from the scope of the invention, it is intended that all matter contained in the above description or shown in the accompanying drawings shall be interpreted as illustrative and not in a limiting sense.

We claim:

1. The method of inserting a draw cord in a prefabricated bag, comprising the steps of gathering a portion of the bag material adjacent the mouth of the bag to form a first set of pleats, gathering another portion of the bag material adjacent the mouth of the bag to form a second set of pleats, thrusting a needle having an eye adjacent its point and threaded with a cord through the first set of pleats, thrusting a second needle having an eye adjacent its point through the second set of pleats, then threading the end of the cord extending from the eye of the first needle in the eye of the second needle, withdrawing both needles from the pleats to pull the cord through the pleats, and securing together the ends of the cord.

2. The method of inserting a draw cord in a prefabricated bag, comprising the steps of gathering a portion of the bag fabric adjacent the mouth of the bag to form a first set of pleats, gathering another portion of the bag fabric adjacent the mouth of the bag to form a second set of pleats, thrusting a needle having an eye adjacent its point and threaded with a cord through the first set of pleats, thrusting a second needle having an eye adjacent its point through the second set of pleats, then threading the end of the cord extending from the eye of the first needle in the eye of the second needle, withdrawing both needles from the pleats to pull the cord through the pleats, cutting the cord at a point between the eye of the first needle and the bag, and securing together the two ends of the resultant length of cord.

3. The method of inserting a draw cord in a prefabricated bag, comprising the steps of gathering the material of one side wall of the bag adjacent its mouth into a set of pleats, gathering the material of the opposite side wall of the bag adjacent its mouth to form a second set of pleats, thrusting a needle having an eye adjacent its point and threaded with a cord through the first set of pleats, thrusting a second needle having an eye adjacent its point through the second set of pleats, then threading the end of the cord extending from the eye of the first needle in the eye of the second needle, withdrawing both needles from the pleats to pull the cord through the pleats, cutting the cord at a point between the eye of the first needle and the bag, and stapling together the two ends of the resultant length of cord.

4. Apparatus for inserting a draw cord in a bag, comprising a support, a pleating device mounted on said support for gathering portions of the material of a bag adjacent its mouth into two sets of pleats, and a needle unit mounted on said support adjacent the pleating device, said unit comprising two needles each having eyes adjacent their points, means mounting said needles for movement on said support into and out of the respective sets of pleats, and means mounted on said support intermediate the pleating device and needle unit for securing together

the ends of a cord inserted into said pleats by said needles.

5. Apparatus for inserting a draw cord in a bag, comprising a support, a pleating device mounted on said support for gathering portions of the material of a bag adjacent its mouth into two sets of pleats, and a needle unit mounted on said support adjacent the pleating device, said unit comprising two needles each having eyes adjacent their points, means mounting said needles for movement on said support into and out of the respective sets of pleats, and a cord cutting and fastening device mounted on said support intermediate the pleating device and needle unit for cutting a cord inserted into said pleats by said needles subsequent to movement of the needles out of the pleats, and for fastening together the ends of the resultant length of cord.

6. Apparatus for inserting a draw cord in a bag, comprising a support, a pleating device mounted on said support for gathering portions of the material of a bag adjacent its mouth into two sets of pleats, and a needle unit mounted on said support adjacent the pleating device, said unit comprising two needles each having eyes adjacent their points, means mounting said needles for movement on said support into and out of the respective sets of pleats, and a cord cutting and stapling device mounted on said support intermediate the pleating device and needle unit for substantially simultaneously cutting a cord inserted into said pleats by said needles subsequent to movement of the needles out of the pleats, and stapling together the ends of the resultant length of cord.

7. Apparatus for inserting a draw cord in a bag, comprising a support, a pleating device mounted on said support including means movable from a retracted position to a pleating position for pleating opposite side walls of a bag adjacent its mouth, means under control of an operator for moving said pleating means to pleating position and releasable to retract the pleating means, a pair of needles mounted on said support for movement toward and away from the pleating device and positioned to be thrust through the respective pleated side walls of the bag, means on the support coupled to the needles for moving them, means controlling said needle-moving means for causing movement of the needles toward the pleating device in response to completion of movement of said pleating means to pleating position, and for causing movement of the needles away from the pleating device in response to release of said operator-controlled means and prior to retracting movement of the pleating means, a cord cutting and fastening device on said support adjacent the pleating device and in line with the path of the needles for cutting a cord inserted into the bag by the needles subsequent to movement of the needles away from the pleating device, and for fastening together the ends of the resultant length of cord.

8. Apparatus as set forth in claim 7, further including means for actuating the cutting and fastening device in response to movement of the needles away from the pleating device.

9. Apparatus for inserting a draw cord in a bag, comprising a support, a pleating device mounted on said support including means movable from a retracted position to a pleating position for pleating opposite side walls of a bag adjacent its mouth, means under control of an operator for moving said pleating means to pleat-

ing position and releasable to retract the pleating means, a pair of needles mounted on said support for movement toward and away from the pleating device and positioned to be thrust through the respective pleated side walls of the bag, means on the support coupled to the needles for moving them, means controlling said needle-moving means for causing movement of the needles toward the pleating device in response to completion of movement of said pleating means to pleating position, and for causing movement of the needles away from the pleating device in response to release of said operator-controlled means and prior to retracting movement of the pleating means, both needles having eyes adjacent their points and one needle being hollow for passage of a cord therethrough.

10. Apparatus for inserting a draw cord in a bag, comprising a support, a pleating device mounted on said support including means movable from a retracted position to a pleating position for pleating opposite side walls of a bag adjacent its mouth, means under control of an operator for moving said pleating means to pleating position and releasable to retract the pleating means, a pair of needles mounted on said support for movement toward and away from the pleating device and positioned to be thrust through the respective pleated side walls of the bag, means on the support coupled to the needles for moving them, means controlling said needle-moving means for causing movement of the needles toward the pleating device in response to completion of movement of said pleating means to pleating position, and for causing movement of the needles away from the pleating device in response to release of said operator-controlled means and prior to retracting movement of the pleating means, both needles having eyes adjacent their points and one needle being hollow for passage of a cord therethrough.

11. Apparatus for inserting a draw cord in a bag, comprising a support, a pleating device mounted on said support having two sets of pleating pins movable with respect to two sets of fixed pleating pins for pleating opposite side walls of a bag adjacent its mouth, means under control of an operator for moving said movable pins to pleating position and releasable to retract them, a pair of needles mounted on said support for movement toward and away from the pleating device and positioned to be thrust through the respective pleated side walls of the bag, means on the support coupled to the needles for moving them, and means controlling said needle-moving means for causing movement of the needles toward the pleating device in response to completion of movement of said movable pins to pleating position, and for causing movement of the needles away from the pleating device in response to release of said operator-controlled means and prior to retracting movement of the movable pins, and a cord cutting and stapling device on said support adjacent the pleating device and in line with the path of the needles for cutting a cord inserted into the bag by the needles subsequent to movement of the needles away from the pleating device, and for fastening together the ends of the resultant length of cord, and means for actuating the cutting and stapling device in response to movement of the needles away from the pleating device.

12. Apparatus for inserting a draw cord in a bag, comprising a support, a pleating device mounted on said support having two sets of pleating pins movable with respect to two sets of fixed pleating pins for pleating opposite side walls of a bag adjacent its mouth, means under control of an operator for moving said movable pins to pleating position and releasable to retract them, a pair of needles mounted on said support for movement toward and away from the pleating device and positioned to be thrust through the respective pleated side walls of the bag, means on the support coupled to the needles for moving them, and means controlling said needle-moving means for causing movement of the needles toward the pleating device in response to completion of movement of said movable pins to pleating position, and for causing movement of the needles away from the pleating device in response to release of said operator-controlled means and prior to retracting movement of the movable pins, and a cord cutting and stapling device on said support adjacent the pleating device and in line with the path of the needles for cutting a cord inserted into the bag by the needles subsequent to movement of the needles away from the pleating device, and for fastening together the ends of the resultant length of cord, and means for actuating the cutting and stapling device in response to movement of the needles away from the pleating device.

12. Apparatus for inserting a draw cord in a bag, comprising a support, a pleating device mounted on said support having two sets of pleating pins movable with respect to two sets of fixed pleating pins for pleating opposite side walls of a bag adjacent its mouth, an expansible chamber type fluid motor coupled to the movable pleating pins for moving them between a retracted position and a pleating position, a pair of needles mounted on said support for movement toward and away from the pleating device and positioned to be thrust through the respective pleated side walls of the bag, an expansible chamber type fluid motor coupled to the needles for moving them, a cord cutting and stapling device on said support adjacent the pleating device and in line with the path of the needles for cutting a cord inserted into the bag by the needles subsequent to movement of the needles away from the pleating device and for stapling together the ends of the resultant length of cord, an expansible chamber type fluid motor coupled to the cutting and stapling device for operating it, operator-controlled valve means controlling the pin-moving actuable to cause the motor to move the pins from retracted position to pleating position and releasable to permit the motor to retract the pins, valve means controlling the needle-moving motor and controlled by the pin-moving motor to cause the needle-moving motor to move
